(57) **CLAIM**

The ornamental design for a game board having a set of game pieces, as shown and described.

DESCRIPTION

1. Game board having a set of game pieces

1.1 is a top, right, front perspective view of a game board having a set of game pieces comprising a game board and a set of game pieces, showing our new design;

1.2 is a top, right, front perspective view showing the game board portion separately for clarity of disclosure;

1.3 is a back, left, top perspective view thereof;

1.4 is a bottom plan view thereof;

1.5 is a top plan view of the game pieces shown separately from the game board for clarity of disclosure;

1.6 is a bottom plan view thereof;

1.7 is a front elevational view thereof;

1.8 is a back elevational view thereof;

1.9 is a left elevational view thereof; and

1.10 is a right elevational view thereof.
